CLAMP

Thomas Pesci, Raritan, N. J.

Application October 25, 1934, Serial No. 749,886

2 Claims. (Cl. 24—250)

My invention relates to improvements in a clamp, and particularly to a clamp for handling large thin sheets of material, such as linoleum, felt base floor covering, and the like.

5 My improved clamp is adapted for removing sheets of material from the printing machine, while the paint upon the sheet is wet, and placing the sheet upon the drying racks.

The practice heretofore has been to operate 10 the printing machine for dropping an extra double border between the adjacent rug designs. The extra border was provided for the purpose of handling the sheet, and as the border was eighteen inches wide, and as long as the width of 15 the sheet, a considerable amount of material was lost, and also the time required to print the extra border.

The object of my invention is to provide a clamp 20 for conveniently handling large sheets of floor covering, and which will engage only a very narrow portion of the selvage.

A further object is to construct a clamp with a rigid base forming one clamp jaw, and hinging a movable clamp jaw of smaller dimensions upon 25 the base, whereby the entire clamp may be as much as nine feet in length and adapted for receiving the entire length of one edge of a rug, or sheet of floor covering.

A further object is to provide a series of 30 devices arranged at spaced intervals throughout the length of the base for pressing the clamp plate tightly upon the sheet of material.

A further object is to provide a connecting 35 bar for simultaneously operating all of the clamp actuating devices.

A further object is to provide clamp plate actuating devices which are movable in one direction for engaging the clamp jaws and movable in the opposite direction for opening the jaws.

40 A further object is to provide a series of levers for operating the movable clamp jaw and provide a novel means for pivotally mounting the levers upon the base, whereby the levers may be adjusted relatively to the movable jaw, and the levers may 45 be so adjusted without disconnecting the levers from the connecting bar to which all the levers are connected.

These together with various other novel features of construction and arrangement of the 50 parts, which will be more fully hereinafter described and claimed, constitute my invention.

Referring to the accompanying drawing:—Fig. 1 is a plan view of my improved clamp.

Fig. 2 is an end view of Fig. 1, drawn on a larger 55 scale.

Fig. 3 is a transverse sectional view on line 3—3 of Fig. 1, drawn on a larger scale and showing the clamp jaws in the open position.

60 Fig. 4 is an enlarged plan view of a portion of the clamp showing the jaws in the open position.

In the drawing, in which like reference characters refer to like parts, 5 represents the clamp comprising a base 6, preferably formed of a strip of wood, having the length of the entire clamp and of rectangular cross section, forming a flat bottom supporting surface, and a top bearing surface 7 for the movable parts of the clamp. One longitudinal upper edge portion of the base forms a clamp jaw 8. Said base is provided with a longitudinal groove 9 for better gripping a thin sheet of 10 material 10, when engaged by the jaws.

A movable clamp plate 12 is hinged upon the top bearing surface 7 of the base by hinges 14. The clamp plate 12 is of angular cross section, preferably formed of metal, and having a member or bead 15 extending the entire length of the outer longitudinal edge portion of the clamp plate and forming the movable jaw of the clamp. The bead 15 is located adjacent to the groove 9 formed in the base and tends to deflect the sheet 20 of material 10 into the groove 9 and securely grip the edge of the sheet.

Stop pins 17 are secured upon the base 6 and pass freely through holes 18 formed through the clamp plate 12. Said pins are located adjacent to the groove 9 and limit the distance the clamp jaws may embrace the edge of the sheet of material.

A series of clamp plate actuating devices is mounted upon the top bearing surface 7 of the 30 base 6 for engaging and moving the clamp plate 12 about the hinges 14, for opening and closing the jaws. Said devices comprise levers 20 rotatably mounted upon pivot pins 21 extending 35 through the base.

Each pivot pin 21 is provided with a head 22, located upon the under side of the base, and a clamp nut 23, in threaded engagement with the pin and located upon the bearing surface 7 of the base, for securely clamping the pin 21 upon the base. The pin 21 projects above the top bearing surface of the base and forms an axis for the lever 20. Said axis extends perpendicular to said bearing surface 7 and at right angles to the axis of the hinges 14 carrying the 40 plate 12. The lever 20 is held upon the pin 21 by a nut 24, and the lever swings over and beyond the line of the axis of the clamp plate 12 45 by a distance, and biases the plane in which the clamp plate swings.

An arm 25 of the lever 20 is provided for moving the clamp plate 12 about the hinges 14 and into the closed position of the jaws for tightly clamping the sheet of material between the jaws.

The lever 20 is adjustable upon the pin 21 by 50 means of a number of washers 26, located between the clamp nut 23 and a sleeve 27. Said sleeve 27 may be an integral part of the nut 24, or it may be made in the form of a separate sleeve. The washers form spacing means be- 55

tween the clamp nut 23 and the lower end of the sleeve 27 and limit the distance the nut 24 may be screwed toward the clamp nut 23, so that the lever will have the proper bearing action upon the movable clamp plate 12 as shown in Fig. 2. By removing one or more of the washers 26 the nut 24 may be screwed closer to the clamp nut 23, so that the lever will press more tightly upon the clamp plate 12 and increase the clamping action of the jaws. The diameter of the sleeve 27 is greater than that of the washers 26 so that the washers will be readily removable through the aperture formed in the lever for the sleeve. By removing the nut 24 and the sleeve 27, the washers will fall through the aperture formed in the lever when the entire clamp is inverted. By this arrangement a washer 26 may be removed without removing the lever from the pivot pin 21.

The levers 20 are supported upon cleats 28, which are secured upon the base 6. The levers slide over the cleats 28, and said cleats support the levers against the under surface of the nuts 24. By removing one or more washers 26 from the pivot pins, any lost motion between the levers 25 and the clamp plate 12 may be compensated for, and all the levers, which are located at spaced intervals along the length of the clamp, may be separately adjusted so as to exert equal pressures upon the clamp plate 12.

30 The clamp plate 12 is moved to open the jaws by an extension part 29 formed upon each lever. The part 29 engages an angle-clip 30, secured by brazing upon the under side of the plate 12. One member of the angle clip 30 extends obliquely 35 relatively to the clamp plate and extends beyond the axis of the hinge 14, toward the pivot pin 21. When the lever is moved in one direction about the pin 21, the extension part 29 of the lever will take against the clip 30 and tilt the clamp plate 12 to the open position, shown in Figs. 3 and 4, in which open position the clamp plate is held by the part 29 of the lever until the latter is moved to again close the clamp plate upon the jaw 8 of the base.

45 The clamp plate actuating devices are arranged for simultaneous action by a connecting bar 31 extending parallel with the length of the base, and pivotally connected by pins 32 with the arms 33 of the levers 20.

50 The connecting bar 31 consists of two relatively light weight plates 34 and 35.

Said plates 34 and 35 extend parallel to each other and are held in spaced relation by spacing blocks 36 rigidly secured between said plates by 55 rivets 37, thus forming a rigid connecting bar.

A detachable hand tool 38 is provided for operating the clamp plate actuating devices. The tool 38 consists of a handle bar 39, bifurcated at one end. The portions 40 and 41 are inserted 60 between the top and bottom plates 34 and 35 of the connecting bar 31, and embrace the arm 33 of one of the levers 20, for turning all the levers simultaneously.

65 A handle, or harness 42 is provided upon the base. Said handle 42 is formed of flexible leather straps 43, 44 and 45 secured to the upper and lower surface of the base 6, at different points throughout the length of the latter. The straps 43 and 44 converge and are secured together and 70 form a handle. A plate 46 is secured between the central portions of the straps 43 and 44. Said plate has a hole 47 formed therein for the insertion of a hook. The straps 43 and 44 extend 75 under the base 6 and form shoes upon which the

base may slide over the floor when dragging a large sheet of floor covering.

The base 6, which forms the lower clamping jaw is made wider than the clamp plate 12, which forms the movable jaw. The relatively greater width of the base forms the wide bearing surface 1 for the levers 20, so that the latter may swing into a position to allow the clamp plate 12 to open. The pivot pins 21 are mounted upon said bearing surface of the base and are located 10 upon the side of the hinges 14 opposite to the clamp jaws. The levers 20 swing in a plane parallel with said bearing surface 1 and pass freely above the hinges 14 into engagement with the clamp plate 12, which latter is positioned obliquely to the base, when in the open position.

The operation of my invention is as follows; the tool 38 is placed upon any one of the levers 20 for turning them into the position shown in Figs. 3 and 4 to open the clamp plate to receive the 20 edge of a sheet of floor covering 10 between the jaws. The stop pins 17 limit the distance the jaws may extend over the sheet. The hand tool 38 is operated to simultaneously turn all the levers 20 into the position shown in Figs. 1 and 2, 25 in which position the arms 25 of the levers engage the clamp plate 12 at various points throughout the length of the latter and rigidly clamp the jaws in engaging position.

30 By my novel adjusting means the levers may be adjusted to vary the pressure of the levers upon the movable clamp plate, without disconnecting the levers from the connecting bar 31.

Various changes in the details of construction and the arrangement of the parts may be made 35 without departing from my invention.

I claim:—

1. A clamp for gripping the edge of a large sheet of linoleum or the like, comprising a relatively long base forming a clamp jaw along one 40 of its longitudinal edges, a clamp plate forming a jaw coacting with the first mentioned jaw, hinges secured to the base and to the opposite edge of the clamp plate relatively to the jaw upon the latter, pivot pins secured upon the base having their axes perpendicular to the base and at right angles to the axis of the clamp plate, levers rotatably mounted upon said pivot pins, a part upon each lever arranged for engaging the clamp plate for turning it about the hinges to close said 45 jaws, a clip upon the clamp plate arranged to be engaged by one of said levers for opening the jaws, a connecting bar connecting the levers for simultaneous operation, and an operating hand tool detachably mounted upon a lever.

50 2. A clamp plate comprising a base having a clamp jaw located along one longitudinal edge portion, a clamp plate having a clamp jaw located along one edge portion and coacting with the jaw upon the base, a hinge secured upon the base and upon the rear edge portion of said plate opposite to the jaw, a plurality of levers pivotally mounted upon said base, one arm of each lever arranged for engaging and moving the clamp plate about said hinge to close the jaws, a connecting bar pivotally connected with said levers for imparting simultaneous movement to said levers, an angle-clip secured upon said clamp plate and positioned adjacent to said hinge, an extension upon a lever positioned between the 55 angle-clip and the clamp plate for engagement with said clip for moving the clamp plate about the hinge and opening the jaws.
